Patented May 5, 1914.

UNITED STATES PATENT OFFICE.

NOAH YODER, OF HUBBARD, OREGON.

FENCE-WIRE HOLDER.

1,095,614.

Specification of Letters Patent.

Patented May 5, 1914.

Application filed July 10, 1913. Serial No. 778,333.

To all whom it may concern:

Be it known that I, NOAH YODER, citizen of the United States, residing at Hubbard, in the county of Marion and State of Oregon, have invented certain new and useful improvements in Fence-Wire Holders, of which the following is a specification.

This invention relates to improvements in fence posts employed in connection with wire fences, and has for one of its objects to provide a simply constructed device whereby the strand wires are firmly supported in position and readily detached or attached when required.

Another object of the invention is to provide a simply constructed device which may be applied to posts of various forms and to posts constructed of different materials, and whereby the strand wires are firmly locked to the post.

With these and other objects in view the invention consists in certain novel features of construction as hereinafter shown and described and then specifically pointed out in the claims.

The improved device may be applied to posts of various forms and constructions, and for the purpose of illustration the device is shown applied to various forms of posts, and in the drawings thus employed: Figure 1 is a side elevation of a conventional metal post with the improvement applied. Fig. 2 is a section on the line 2-2 of Fig. 1. Fig. 3 is a detached perspective view of the lock bar. Fig. 4 is a detached perspective view of the locking pawl. Fig. 5 is a sectional detail illustrating the manner of applying the improved device to a post constructed of concrete. Figs. 6 and 7 are views similar to Fig. 5, illustrating the improved device applied to posts of wood or like material.

Corresponding and like parts are referred to in the following description and indicated in all the views of the drawings by the same reference characters.

The improved post may be constructed of any required size or of any suitable material, but for the purpose of illustration is shown in Figs. 1 and 2 constructed of metal in tubular form, with a body portion 10 and with laterally directed lower parts 11 to form an anchor to prevent the post from being lifted from the ground. The body portion 10 is formed with outwardly directed flanges 12 spaced slightly apart and

with a lock bar 14 disposed between the flanges. The outer edge of the bar comes flush with the outer edges of the flanges, as shown. The flanges 12 are provided respectively with inwardly and downwardly directed slots 15, the slots being preferably formed with the outer ends wider than the inner ends to facilitate the entrance of the strand wires. As many slots will be employed as there are strand wires in the fence, and will be located at any required distance apart. A rivet 17 extends through the flanges near their upper ends, and a similar rivet 18 extends through the flanges nearer the ground as shown. The lock bar 14 is provided with slots 19-20 through which the rivets 17-18 extend when the bar is disposed in position between the flanges. The bar 14 is provided with oblique slots 21 corresponding in number and location with the slots 15 of the flanges but inclining inwardly and upwardly, or reversely to the slots 15. The outer edges of the flanges are provided with transverse stop recesses 22, while the bar 14 is provided with a plurality of ratchet teeth 24. Bearing over the outer edges of the flanges 12 and of the bar 14 is a resilient pawl device 25 having ears 26 bearing upon opposite sides of the flanged portion 85 of the post and pivotally engaging the outer ends of the rivet 18. The terminals of the member 25 are bent inwardly to engage respectively in the notches 22 and with the teeth 24 of the lock bar. With a device thus constructed and arranged when the strand wires are to be applied the pawl 25 is usually released and the bar 14 drawn to its upper position, or as far as the slots 19-20 will permit, which movement brings 90 the slots 21 of the bar 14 into their upper position or with the opposite outer ends of the slots 21 opposite the open outer ends of the slots 15, or in other words, with all of the slots at their open ends in transverse alinement. The strand wires are then inserted into the coacting slots and the bar 14 forced downwardly against the resistance of the member 25, which movement will force the strand wires into the slots 15, the slots 21 crossing 105 the slots 15-16 as illustrated in Fig. 1, and thus locking the strand wires firmly in position. As the bar is forced downwardly the member 25 engages in the teeth 24 and thus effectually prevents any reverse movement. By this simple means the strand wires are firmly locked in position and all 110

movement effectually prevented, while at the same time one or more strand wires may be readily released by forcibly disengaging the member 25 and throwing the member 5 14 upwardly. Any suitable means may be employed for forcing the member 14 downwardly into position against the resistance of the member 25, but an effectual means for accomplishing this result consists in 10 lever 27 inserted by one end through an aperture 28 in the body portion 10 of the post as illustrated in Fig. 1.

The improved device may be applied to posts of various forms, as before stated, and 15 when employed in connection with a concrete post 29, as illustrated in Fig. 5, the flange elements are arranged in the form of flat plates 30—31 embedded by their inner edges within the material of the post and with the 20 slotted edges projecting beyond the same. The lock bar 14 is precisely the same as in the structure shown in Figs. 1, 2 and 3, and operates in the same manner. In Fig. 6 an arrangement is shown whereby the device is 25 applied to square or oblong posts, while in Fig. 7 the device is shown arranged in connection with a round or circular post, but it will be understood that these various modifications do not constitute a departure from 30 the principle of the invention or sacrifice any of its advantages, as the same results are produced in all of the various modifications and in substantially the same manner.

Having thus described the invention, what 35 is claimed as new is:

1. A device of the class described compris-

ing a supporting member having a plurality of obliquely directed open slots, a locking member movable relative to said supporting member and having corresponding oblique 40 open slots directed reversely to the slots of the supporting member, one of said members having ratchet teeth and the other member having a locking pawl engaging said teeth. 45

2. A device of the class described comprising a support having a plurality of obliquely directed open slots and a stop recess, a locking member movable relative to said support and having corresponding 50 oblique open slots directed reversely to the slots of the support and a plurality of ratchet teeth, and a locking pawl pivoted to said support and engaging said stop recess at one end and engaging said ratchet teeth 55 one at a time by the other end.

3. A device of the class described comprising a support having a plurality of obliquely directed open slots, a locking member movable relative to said support and 60 having corresponding oblique open slots directed reversely to the slots of the support and with a plurality of ratchet teeth, and a locking pawl connected to said support and engaging said ratchet teeth one at a time. 65

In testimony whereof I affix my signature in presence of two witnesses.

NOAH YODER. [L. S.]
